(57) **CLAIM**

The ornamental design for an adjustable modeling construction piece, as shown and described.

DESCRIPTION

FIG. 1 is a perspective view of the adjustable modeling construction piece.

FIG. 2 is a second perspective view of the adjustable modeling piece.

FIG. 3 is a front elevational view of the adjustable modeling construction piece.

FIG. 4 is a rear elevational view thereof.

FIG. 5 is a top plan view thereof.

FIG. 6 is a bottom plan view thereof, wherein portions of the drawing shown in broken lines form no part of the claimed design.

FIG. 7 is a right side elevational view thereof; and,

FIG. 8 is a left side elevational view thereof.
